(57) **CLAIM**

We claim the ornamental design for a utensil shaft, as shown and described.

DESCRIPTION

FIG. 1 is a top perspective view of a utensil shaft showing our new design;

FIG. 2 is a top plan view thereof;

FIG. 3 is a right side elevational view thereof, the left side elevational view being a mirror image;

FIG. 4 is a bottom plan view thereof;

FIG. 5 is a front elevational view thereof;

FIG. 6 is rear elevational view thereof;

FIG. 7 is a top perspective view of the utensil shaft, showing a utensil in a first alternate environment;

FIG. 8 is a top plan view of FIG. 7;

FIG. 9 is right side elevational view of FIG. 7, the left side elevational view being a mirror image;

FIG. 10 is bottom plan view of FIG. 7;

FIG. 11 is a front elevational view of FIG. 7;

FIG. 12 is a rear elevational view of FIG. 7;

FIG. 13 is a top perspective view of the utensil shaft, showing a utensil in a second alternate environment;

FIG. 14 is a top plan view of FIG. 13;

FIG. 15 is a right side elevational view of FIG. 13, the left side elevational view being a mirror image;

FIG. 16 is a bottom plan view of FIG. 13;

FIG. 17 is a front elevational view of FIG. 13;

FIG. 18 is rear elevational view of FIG. 13;

FIG. 19 is a top perspective view of the utensil shaft, showing a utensil in a third alternate environment;

FIG. 20 is a top plan view of FIG. 19;

FIG. 21 is a right side elevational view of FIG. 19, the left side elevational view being a mirror image;

FIG. 22 is a bottom plan view of FIG. 19;

FIG. 23 is a front elevational view of FIG. 19;

FIG. 24 is a rear elevational view of FIG. 19;

FIG. 25 is a top perspective view of the utensil shaft, showing a utensil in a fourth alternate environment;

FIG. 26 is a top plan view of FIG. 25;

FIG. 27 is a right side elevational view of FIG. 25, the left side elevational view being a mirror image;

FIG. 28 is a bottom plan view of FIG. 25;

FIG. 29 is a front elevational view of FIG. 25; and,

FIG. 30 is a rear elevational view of FIG. 25.

The variations of a utensil shown in broken lines are for environmental purposes only and form no part of the claimed design.
